(57) **CLAIM**

I claim, the ornamental design for a bracelet, as shown and described.

DESCRIPTION

FIG. 1 is a perspective view of a bracelet, showing my new design;

FIG. 2 is a top plan view thereof;

FIG. 3 is a bottom plan view thereof;

FIG. 4 is front elevation view thereof;

FIG. 5 is a rear elevation view thereof;

FIG. 6 is a side elevation view thereof taken from the right of FIG. 4; and,

FIG. 7 is a side elevation view thereof taken from the left of FIG. 4.

The broken lines shown in the drawings represent unclaimed portions of the bracelet and form no part of the claimed design.
